(57) **CLAIM**

I claim the ornamental design for a tire, as shown and described.

DESCRIPTION

FIG. 1 is a front view of a tire, showing my new design; and, FIG. 2, is a side view thereof.

In the drawings, the broken lines defining detail in the recessed portion of the tread grooves, the sidewall, inner bead and the peripheral boundary between the claimed tire tread and the unclaimed sidewall depict environmental subject matter that forms no part of the claimed design.
